DRAFT REGULATING APPARATUS

Richard A. Walker, St. Joseph, Mo.

Application May 13, 1943, Serial No. 486,793

4 Claims. (Cl. 236—45)

My invention relates to improvements in draft regulating apparatus. It relates particularly to the type of draft regulating apparatus in which a damper plate, pivoted on a horizontal axis in a ring plate adapted to be fastened to the air intake end of a draft pipe of a smoke pipe, has a larger surface area below its axis than above it, whereby a sufficient outside atmospheric pressure will swing the damper plate from a closed position in the plane of the ring plate to an open position at an angle thereto.

One of the objects of my invention is the provision of novel means for hinging the damper plate in the ring plate by which a minimum of friction resisting the swinging of the damper will be afforded; which provides novel bearing means for the pintles supporting the damper plate that will prevent the accumulation of rust and other deposits where they will interfere with the free turning of the pintles in the bearing means; which will hold the edges of the damper plate spaced from the inner edge of the ring plate, and will eliminate the need of washers or gaskets for effecting such spacing, which is simple, cheap to manufacture and may be quickly and easily assembled in operative condition.

A further object of my invention is the provision of novel counter balancing means for the damper plate, including a novel counterbalancing weight that may be formed from scrap pieces of metal assembled into an integral structure which can be utilized and handled as a unit.

The novel features of my invention are hereinafter fully described and claimed.

In the accompanying drawing, which illustrates my invention,

Fig. 1 is an outside elevation of my improved draft regulating apparatus, showing the damper plate in the closed position, and a portion of the damper stop plate partly broken away.

Fig. 2 is an inside elevation of what is shown in Fig. 1.

Fig. 3 is a section on the plane of the line 3—3 of Fig. 1.

Fig. 4 is an enlarged outside elevation of a portion of the ring plate and a portion of the damper plate, showing one of the two pintles operatively engaged with one of the bearing plates, portions of the stop plate being shown in solid and dotted lines respectively.

Fig. 5 is an outside elevation of a portion of the ring plate and a portion of the damper plate, showing the other pintle operatively engaged with the other bearing plate; which is shown in vertical section.

Fig. 6 is a section on the line 6—6 of Fig. 4, the stop plate being omitted.

Fig. 7 is an enlarged vertical section on the line 7—7 of Fig. 2.

Fig. 8 is an enlarged plan view of a blank from which one of the bearing plates is to be formed.

Fig. 9 is a horizontal section on the line 9—9 of Fig. 11 of one of the bearing plates, enlarged.

Fig. 10 is an enlarged inside elevation of one of the bearing plates.

Fig. 11 is a side elevation of one of the bearing plates, enlarged.

Fig. 12 is an outside elevation, enlarged, of a portion of that part of the ring plate shown in

Fig. 5, showing the outer end portion of the adjacent pintle operatively mounted in the adjacent bearing plate, which is shown in vertical section to disclose the projection in the notch against which the outer end of the pintle bears.

20 Similar characters of reference designate similar parts in the different views.

1 designates a ring plate having an annular peripheral flange 2 adapted to be snugly fitted in the air intake end of a draft pipe 3, Fig. 3, 25 which usually forms the air intake of a T joint mounted in a smoke pipe, not shown.

4 designates a circular damper plate disposed within and spaced slightly from the inner edge of the ring plate.

30 5 and 6 designate respectively two longitudinally aligned horizontal pintles rigidly fastened to the damper plate 4 in a plane above the horizontal diameter of the damper plate, which pintles are in the axis of the damper plate, so that 35 there is more surface area of the damper plate below the axis of the damper plate than the surface area above said axis. Any suitable means for rigidly attaching the pintles to the damper plate may be employed.

40 In the specific means shown in the drawing, the pintle 5, Fig. 5, is mounted in three aligned horizontal depressions 7, 8 and 9, the end depressions 7 and 9 being depressed into one side of the damper plate, and the middle depression 8 being depressed into the opposite side of the

45 damper plate. The pintle 5 projects from the damper plate at its outer end, and its inner end bears against the closed inner end of the inner depression 9. The middle depression 8 is pinched 50 so as to hold the pintle 5 tightly in its operative position.

The other pintle 6, Figs. 4 and 5, is similarly mounted in three depressions 10, 11 and 12, which align with the depressions 7, 8 and 9. The inner depression 12, as the damper plate is originally

made, at its inner end merges into a concentric arcuate groove 13 in the damper plate, so that the pintle 6 may be inserted into the depressions 10, 11 and 12 from the inner side into its operative position.

When this has been done, the inner end of the depression 12 is indented, as shown in Figs. 4 and 5 at 14 to hold the pintle 6 from inward movement. The reasons for this construction will be explained hereinafter.

Alined with the axis of the damper plate 4 are two oppositely disposed notches 15 in the inner edge of the ring plate 1. An axial projection 16 extends inwardly from the closed end of each notch 15, and the outer ends of the pintles 5 and 6 respectively bear against the inner ends of said projections 16, thus holding the damper plate 4 from contacting at its outer edge with the inner edge of the ring plate 1.

For pivotally supporting the pintles 5 and 6 respectively in their operative positions, two bearing plates generally designated by 17, are respectively mounted in the notches 15.

A description of one bearing plate 17 will suffice for both as they are constructed alike.

In the construction of the bearing plate, a blank, shown in Fig. 8, is cut from a flat sheet of metal, said blank having extending from its middle portion 18 two arms 19, and having extending at right angles to the arms 19 at opposite edges of the middle portion 18, two wing portions 20. A pintle receiving opening 21 is punched in the center of the middle portion 18.

The wing portions 20 are bent parallel with each other at one side of the blank, after which the arms 19 are bent at the same side of the blank as the wing portions, but at right angles thereto and to fit against the edges of the wing portions 20 thus forming with the middle portion 18 and arms 19 a closed compartment. The outer portions of the arms 19 beyond the wing portions 20 are disposed parallel with each other and spaced apart the thickness of the ring plate 1.

The outer end portions of the arms 19 respectively embrace opposite sides of the ring plate 1 to which they are rigidly fastened, as by spot welding. The wing portions 20 are disposed horizontally against the adjacent edges of the notches 15, at opposite sides of the projections 16. The outer ends of the wing portions 20 bear against the closed ends of the notches 15, thus spacing the middle portions 18 and their openings 21 from the projections 16 and eliminating liability of accidental disengagement of the pintles 5 and 6 from the bearing plates 17.

In assembling, the pintle 5 is inserted into and fastened in the depressions 1, 8 and 9, as has been described. The damper plate 4 is then inserted in the ring plate 1, as shown in Fig. 1, with the pintle 5 extended into the opening 21 of the adjacent bearing plate 17, and its outer end against the projection 16.

The other pintle 6 is then inserted outwardly into the open inner end of the depression 12, and thence through the depressions 11 and 10 through the opening 21 of the adjacent bearing plate 17, and with its outer end against the adjacent projection 16. The inner end of the depression 12 is then forced inwardly at 14, Figs. 4 and 5, against the inner end of the pintle 6. The pintles 5 and 6, thus, by bearing against the projections 16, hold the damper plate 4 spaced from the inner edge of the ring plate 1, eliminating the need of washers, sometimes provided on the pintles for this purpose.

It will be noted that the outer end portions of the pintles 5 and 6 are completely enclosed in the two closed compartments the bearing plates 17, thus preventing accumulation of rust, sediment or other material that would tend to resist the turning movement of the pintles in the bearing openings 21. These openings are only the length of the thickness of the metal bearing plates, so offer small surface area for rust collection, and permit the damper plate 4 to swing freely in the bearing plates 17.

A stop plate 22 is fastened to the outer side of the ring plate 1 below the axis of the damper plate 4, and engages and holds the latter from swinging outwardly at its lower end past the plane of the ring plate 1. The upper end of the stop plate 22 turns outwardly and is disposed in the path of the portion of the damper plate above the axis, thus limiting the opening movement of the damper plate, when the inward draft through the ring plate swings the damper plate to an open position.

For counterbalancing the damper plate, it has fastened to it above its axis counterbalancing means consisting of the following described parts.

A plurality of metal cups, three as shown, 23, 24 and 25 are nested one inside and in front of the other, the front cup 23 having a concentric annular portion provided at its outer periphery with an annular flange 26 which tightly embraces the periphery of the front portion of the outer cup 25, Fig. 7.

Between the cups 24 and 25 is disposed a disk of metal, as lead, 27. The cups 23, 24 and 25 and lead disk 27 have through them a central row of holes through which extends a bolt, as a rivet 28, which extends through a hole in the damper plate in the vertical center and above the axis thereof. In the cup 23 on the rivet 28 is a sleeve 29 bearing at its inner end against the closed end of the cup 23, and at its outer end against the inner side of the damper plate 4. A sleeve 30 on the rivet 28 bears at one end against the outer side of the damper plate 4 and at its other end against one of two washers 30, the outer one of which bears against the head at the outer end of the rivet 28.

The cups 23, 24 and 25, and disk 27 may be formed from cheap scrap metal, thus replacing the usual brass weights heretofore employed. By assembling the cups and disk, as shown and described, they form an integral structure that can be used and handled as a unit, thus facilitating the assembling of the weight mechanism.

In the operation of the apparatus, the counterbalancing weight mechanism is proportioned so that it will hold the damper plate 4 closed, as shown in the drawing. When the flue draft exceeds a predetermined pressure, the atmospheric pressure from the outside will swing the damper plate 4 inwardly at its lower end and outwardly at its upper end, or counterclockwise, as viewed in Fig. 3, an amount depending upon the increased draft. When the draft in the flue reduces in pressure to the predetermined pressure, the damper plate will return to the closed position, where it will be stopped by striking against the inner side of the stop plate 22, the upper end of which will limit the opening movement of the damper plate.

Modifications of my invention, within the scope of the appended claims, may be made without departing from the spirit of my invention.

What I claim is:

1. In a draft regulating apparatus, a ring plate

adapted to be disposed at the air intake end of a draft pipe and having at its inner edge two oppositely disposed alined notches, each having at its closed end an inwardly extending projection, two bearing plates respectively mounted in said notches and having each a vertical middle portion transverse to said ring plate and having an opening alined with and spaced from the adjacent one of said projections, each bearing plate having extending outwardly from its middle portion two arms which respectively embrace and are rigidly attached to opposite sides of said ring plate at the outer side of the adjacent notch, each bearing plate having one above the other two wing portions extending from its middle portion into the adjacent notch to the closed end thereof and to its said two arms, a damper plate in and spaced at its edges from said ring plate, and two longitudinally alined pintles rigidly fastened to said damper plate and extending respectively from opposite edges thereof through and pivotally mounted in said openings of said bearing plates and bearing at their distant ends against said projections respectively, said damper plate being adapted to be swung, supported by said pintles, from a closed position substantially in the plane of said ring plate to an open position at an angle thereto.

2. In a draft regulating apparatus, a ring plate adapted to be disposed at the air intake end of a draft pipe and having at its inner edge two oppositely disposed alined notches, two bearing plates respectively mounted in said notches and having each a vertical middle portion transverse to said ring plate and having an opening alined with and spaced a substantial distance from the closed end of the adjacent notch, each bearing plate having extending outwardly from its middle portion two arms which respectively embrace and are rigidly attached to opposite sides of said ring plate at the outer side of the adjacent notch, said middle portions, each having at opposite upper and lower edges two horizontal wings extending to said arms and forming with the middle portions and said arms a closed compartment, a damper plate in and spaced at its edges from said ring plate, and two longitudinally alined pintles rigidly fastened to said damper plate and extending respectively from opposite edges thereof through and pivotally mounted in said openings

of said bearing plates and extending through said compartments and bearing at their distant ends against the closed ends respectively of said notches, said damper plate being adapted to be swung, supported by said pintles, from a closed position substantially in the plane of said ring plate to an open position at an angle thereto.

3. In a draft regulating apparatus, a ring plate adapted to be disposed at the air intake end of a draft pipe and having at its inner edge a notch having at its closed end an inwardly extending projection, a bearing plate mounted in said notch and having a vertical middle portion transverse to said ring plate and having an opening alined with and spaced from said projection, said bearing plate having extending outwardly from its middle portion two arms which respectively embrace and are rigidly attached to opposite sides of said ring plate at the outer side of said notch, said bearing plate having one above the other two wing portions extending from its middle portion into the said notch to the closed end thereof and to said two arms, a damper plate in and spaced at its edges from said ring plate, and a pintle rigidly attached to said damper plate and pivotally mounted in said opening and bearing at its outer end against said projection.

4. In a draft regulating apparatus, a ring plate adapted to be disposed at the air intake end of a draft pipe and having at its inner edge a notch, a bearing plate mounted in said notch and having a vertical middle portion transverse to said ring plate and having an opening alined with and spaced a substantial distance from the closed end of said notch, said bearing plate having extending outwardly from its middle portion two vertical arms which respectively embrace and are rigidly attached to opposite sides of said ring plate at the outer side of said notch, said middle portion having at opposite upper and lower edges two horizontal wings extending to said arms and forming therewith and with said middle portion a closed compartment, a damper plate in and spaced at its edges from said ring plate, and a pintle rigidly attached to said damper plate and pivotally mounted in said opening and extending through said compartment and bearing at its outer end against the closed end of said notch.
